UNITED STATES PATENT OFFICE.

WALLACE S. CLARK, OF SCHENECTADY, NEW YORK, ASSIGNOR TO GENERAL ELECTRIC COMPANY, A CORPORATION OF NEW YORK.

MACHINE FOR FORMING TUBES OF SOFT METAL.

SPECIFICATION forming part of Letters Patent No. 732,829, dated July 7, 1903.

Application filed February 8, 1901, Serial No. 46,500. (No model.)

To all whom it may concern:

Be it known that I, WALLACE S. CLARK, a citizen of the United States, residing at Schenectady, county of Schenectady, State of New York, have invented certain new and useful Improvements in Machines for Forming Tubes of Soft Metal, of which the following is a specification.

This invention relates to machines for forming a continuous seamless tube of soft metal, such as lead or an alloy of lead and tin or any other suitable plastic or semiplastic material, such as gutta-percha, india-rubber and its compounds, tar or asphalt compounds, or the like. One use to which such machines are put is covering electric conductors or cables with a sheath of the desired material. The mode of operation consists in leading the conductor or cable through a tubular mandrel 15 which passes into a receptacle for the lead or other material and terminates adjacent to a die, leaving an annular space, through which the plastic material is forced in the shape of a tube closely surrounding the conductor. 20 This process requires that the mandrel shall remain at all times exactly concentric with the die in order that the thickness of the sheath or covering may be uniform.

In the machine embodying my improvements the mandrel and the receptacle for the plastic material are supported on a vertically-movable piston or ram, by means of which they can be raised, so that a stationary annular plunger concentric with the mandrel 35 can enter the receptacle and force the plastic material through the die at the bottom as the receptacle rises. I provide the pedestal on which the receptacle rests with a central chamber open on one side, so that the incased 40 conductor coming down through the die can be led off to one side and reeled up.

In the following description I have for the sake of convenience assumed that the material to be operated on is lead; but it should 45 be clearly understood that I do not thereby intend to limit the use of my machine to any given material.

In the accompanying drawings, Figure 1 is a top plan view of my improved press. Fig. 50 2 is a vertical section thereof on the line 2-2, Fig. 1. Fig. 3 is an enlargement of that por-

tion of Fig. 2 showing the die at the bottom of the lead-receptacle. Fig. 4 is an enlarged vertical section of the lower end of the mandrel. Fig. 5 is an enlarged detail sectional view of a portion of the ram and its packing. Fig. 6 is a cross-section of Fig. 2 on the line 6-6 on an enlarged scale.

The frame of the machine comprises stout pillars or standards A, preferably three in number and placed at the angles of an equilateral triangle. At a given height above their lower ends the standards support a heavy rigid bed-plate B. This is preferably clamped against collars a on the standards 65 by nuts A' engaging with screw-threads a' cut in the standards. The upper ends of the standards are united by a heavy rigid cap-plate C, which is adjustable vertically by means of nuts A² engaging screw-threads a² 70 on the standards above and below said cap-plate. The bed-plate has a central opening to receive the cylinder D, which preferably hangs suspended by a flange d, resting on the bed-plate, and has a brass or similar lining 75 d'. In the lower end of the cylinder is a packed pipe connection D', by means of which fluid-pressure can be conveyed to the cylinder and raise a piston-ram E therein, preferably a tubular structure having a jacket e, of brass 80 or the like, and provided at its lower end with a packing-disk E', of leather or the like, cupped to make a fluid-tight joint and clamped in place by a plate E², held by screws e'. An annular packing E³ surrounds the ram just 85 above the packing E'. At the upper end of the cylinder is an annular semicylindrical packing D², retained in a countersink in the cylinder by a ring D³ and an annular gland D⁴, secured to the top of the cylinder and closely 90 fitting the ram. A pipe F enters the annular space between the ram and the cylinder just below the packing D².

Resting on the top of the ram and firmly attached thereto is a pedestal or space-block G, 95 preferably fluted vertically to give it strength with comparative lightness and containing a central chamber g open on one side, as shown in Fig. 6. The top of the pedestal has a central opening through it, which is counterbored 100 to form a seat for the annular die-block H, having a tubular central neck h passing down

through the opening in the pedestal and there-
in secured, as by a nut h' , screwed upon the
neck and abutting against the under side of
the pedestal top, as shown in Fig. 3. The die-
block has some lateral play on its seat and can
be adjusted by means of set-screws G' , pass-
ing transversely through the upper part of the
pedestal and abutting against the die-block.

In the tubular neck h is screwed a bushing
10 H' , on which rests an annular bolster H^2 , hav-
ing an inwardly-beveled upper edge and an
internal flange h^2 , on which rests the die I ,
consisting of a ring having a beveled upper
edge in line with the beveled edge of the bol-
ster H^2 . The opening through the die is
15 slightly smaller than that through the bolster
and bushing to give plenty of clearance for
the incased conductor leaving the die.

The die-block H forms the bottom of the
20 lead-receptacle K , which has a cylindrical in-
terior and is strengthened by a series of heavy
hoops k , the lower one having ears k' to re-
ceive the bolts K' , by which it is fastened to
the pedestal G . Upright guide-rods L are in-
25 serted into the upper hoops and rise through
holes in the cap-plate, their upper ends being
rigidly connected by a yoke M , adjustably se-
cured to the rods by nuts m . The holes in
the cap-plate are preferably a little larger
30 than the rods, which are accurately guided by
plates N , secured to the cap-plate and having
holes engaging the rods with a sliding fit. A
tubular mandrel P is adjustably secured by
nuts p in a hole at the center of the yoke and
35 passes centrally through a passage-way in the
cap-plate, terminating just above the die I ,
the axis of the mandrel being coincident with
that of the die. The nuts p provide for the
adjustment of the annular space between the
40 die and the end of the mandrel.

A stationary plunger R is secured to the un-
derside of the cap-plate, preferably by means
45 of a flanged collar R' , engaging a flange r on
the plunger and having ears r' to receive the
bolts R^2 , which are preferably hinged to the
cap-plate, as shown in Fig. 2. The plunger
50 is tubular to allow the mandrel to pass
through it, having bushings r^2 screwed into
its ends and fitting the mandrel snugly, so as
55 to center the mandrel accurately. The plun-
ger fits the cylindrical interior of the lead-re-
ceptacle, so that it will enter it and expel the
lead when the receptacle is lifted by the ram.

In order to insure a uniform thickness of the
55 tube or sheath, the end of the mandrel is so
made as to have a swiveling or universal
joint action, so that the pressure of the lead
will hold it concentric with the die and will
automatically center it if accidentally dis-
60 placed. The preferred construction is shown
in Fig. 4, wherein the nozzle P' has a reduced
portion p' provided with a flange p^2 and fit-
ting into a socket in the end of the mandrel,
where it is secured by a bushing P^2 , screwed
65 into the socket. The shoulder p^2 and the up-
per end of the nozzle and the corresponding
faces of the nut and mandrel are curved on

the arcs of concentric spheres, so that the
nozzle has a universal ball-joint action. The
tip p^3 of the nozzle is removable, in order to 70
allow it to be changed or renewed at pleasure.
By properly shaping the outside of the
nozzle and tip the downward pull on them,
due to the friction of the lead flowing over
their surfaces, may be made to balance the 75
upward thrust due to the pressure exerted on
all surfaces within the cylinder. As the pres-
sure in the annular space between the nozzle
and the die is greatest at the point where the
metal is thinnest, the result is to push the 80
nozzle over toward that side of the die where
the metal is thickest, thereby equalizing the
thickness of the metal and evening up the
pressure. The frictional resistance to mo-
tion through the die and core tube or man- 85
drel where the space is narrowest produces a
greater relative interference with the motion
of the metal at that place than where it is
wider, causing pressure to be stored or a
greater back pressure to be produced at that 90
point than where the space is wider. This
results in swinging the movable core-tube lat-
erally and equalizing the space.

The operation of the press when making a
95 tube or applying a sheath to a cable is as fol-
lows: The receptacle is filled with molten
lead, which is allowed to cool sufficiently to
solidify. The ram is then raised by fluid-
pressure, carrying the receptacle up over the
100 stationary plunger and forcing the lead to
escape between the nozzle and the die in the
shape of a seamless tube. If a cable is to be
covered, it is fed down through the mandrel
at the same rate of speed as the formation of
105 the pipe. The lead will continue to flow out
at the bottom of the receptacle until the limit
of movement of the ram is reached. This is
so adjusted that a residue of lead of suitable
thickness—say three inches—remains in the
110 bottom of the receptacle. The fluid-pressure
is then cut off from the pipe D' at the bottom
of the cylinder and a suitable port or cock
opened and pressure admitted through the
pipe F , each pipe D' and F acting as a supply
and exhaust pipe, forcing the ram downward
115 and with it the pedestal, receptacle, man-
drel, guide-rods, and yoke until the top of the
receptacle is below the plunger. A fresh
charge of molten lead is then run into the
receptacle, where it unites with the residue
120 of the former charge, and when it has solidi-
fied the press is ready to form a further
length of pipe. It is evident that this cycle
of steps can be repeated indefinitely, so that
a pipe or sheath of any length can be pro-
125 duced. The finished product is guided off
laterally through the open side of the cham-
ber g .

What I claim as new, and desire to secure
by Letters Patent of the United States, is— 130

1. The combination with a ram and a ped-
estal thereon, of a plunger, a die-block mount-
ed on the pedestal, a bushing screwed into
said die-block, a flanged bolster supported

on said bushing, and a die resting on said bolster.

2. The combination of a downwardly-projecting mandrel, a self-adjusting nozzle secured thereto and independently laterally movable in any horizontal direction under irregularities of lead-pressure, and a die beneath the nozzle.

3. In a lead-press, the combination with a receptacle, of a vertically-adjustable die in its bottom, and a vertically-adjustable mandrel terminating just above said die, said mandrel having a self-adjusting laterally-movable nozzle.

4. In a lead-press, the combination with a tubular mandrel, of a nozzle therefor, and a bushing for securing it to the mandrel, the meeting faces of the nozzle and bushing being on the arc of a sphere.

5. In a lead-press, the combination with a

tubular mandrel having a socket in its end, of a nozzle provided with a reduced portion to enter said socket, and having a flange at its upper end, and a bushing to screw into the socket and abut against said flange, the meeting faces of the socket, nozzle and bushing, being on arcs of spheres.

6. In a lead-press, the combination with a receptacle, of a die, and a stationary mandrel provided with a self-adjusting laterally-movable nozzle having such a tapered surface that the friction of the lead thereon balances the tendency of the pressure to separate the die and mandrel.

In witness whereof I have hereunto set my hand this 6th day of February, 1901.

WALLACE S. CLARK.
